UNITED STATES PATENT OFFICE.

JENS C. JENSEN, OF PENTWATER, MICHIGAN, ASSIGNOR TO ALBERT G. WEIDENSEE, OF PENTWATER, MICHIGAN.

WATER-GAGE COCK.

SPECIFICATION forming part of Letters Patent No. 728,722, dated May 19, 1903.

Application filed December 26, 1902. Serial No. 136,676. (No model.)

To all whom it may concern:

Be it known that I, JENS C. JENSEN, a citizen of the United States, residing at Pentwater, in the county of Oceana and State of Michigan, have invented new and useful Improvements in Water-Gage Cocks, of which the following is a specification.

This invention relates to certain new and useful improvements in water-gage cocks to be used in connection with steam-boilers, and more especially to be used in connection with boilers of marine engines.

The invention consists in the construction and combination of parts hereinafter fully described and claimed.

The objects of my invention are, first, to construct a water-gage cock that will not become clogged by any foreign matter within the boiler; second, to furnish a suitable means for closing the opening between the valve-chamber and the conduit or passage-way into the boiler in order to enable the user to clean or repair the exhaust-valve; third, to furnish an escape-valve that will work quickly and efficiently when mechanically opened, but which will be normally held closed by steam-pressure. These objects I accomplish by means of the mechanism illustrated in the following drawings, in which—

30 Figure 1 is a vertical longitudinal sectional view of a water-gage cock constructed in accordance with my invention. Fig. 2 is a horizontal longitudinal section of the said water-gage cock. Fig. 3 is an inverted plan view 35 of the bent arm that is used to open the exhaust-steam valve. Fig. 4 is a side elevation of the valve-stem of the exhaust-valve, and Fig. 5 is a sectional view of the valve-stem on line *x y* of Fig. 4.

40 The main stem of the water-gage cock which enters the boiler is shown by *a*, and it is provided with the opening *b*, which terminates at one side of the valve, as shown in Fig. 2.

45 *d* is an intermediate chamber for the valve *q*, which valve *q* closes and opens the passage-way between *b* and the chamber *d*. The valve *q* has a valve-stem *W* and a hand-wheel *V*, a threaded cylindrical projection 2, 50 preferably made integral with the stem *a*, with which thread is engaged the threaded collar *t*,

the said collar *t* being provided with an internal screw-thread, which engages with the threaded part of the valve-stem *W*. In order to make a more tight fit, I provide a collar *u*, 55 which is threaded and engages with the upper and outer threaded part of the collar *t*, and between the upper end of the collar *t* and the collar *u* I provide a steam-tight packing, as shown by *Z*. 60

The passage-way between the chamber *f* and the chamber *d* is shown by *e*, which passage-way is always open.

A stem *a* is provided with the screw-thread *r*, by means of which the stem is engaged 65 with the walls of the boiler. The part shown by *P*, which is preferably not threaded, projects into the boiler beyond the inner surface thereof a suitable distance to prevent the opening to the passage-way *b* from becoming 70 clogged by scales or any foreign substance within the boiler.

When the valve *q* is withdrawn from its seat, the steam will pass freely into the chamber *f*, creating a pressure in said chamber. 75 From the chamber *f* is the internally-threaded projection *3*. (Shown in Fig. 1.) Fitting into the projection *3* is the collar *I*, which has an unthreaded opening for the valve-stem of valve *h*. The inner end of the collar 80 *I* forms the valve-seat of the valve *h*. The valve-stem of valve *h* is provided with a series of channels, as shown by *g*, through which channels the steam passes freely when the valve *h* is raised from its seat. The valve-stem of *h* is also provided with a groove, as in Figs. 1 and 4, with which the bifurcated arm *m* engages. The valve *h* is operated by means of the bent arm *m* and lever *n*. The arm passes loosely through the opening *S* in 85 the rear end of the main stem *a*. This lever *n* is pivoted at *O* to a lug on the stem *a* and at *O'* to the upper end of the arm *m*, as shown clearly in Fig. 1.

The operation of my invention is as follows: The stem *a* is screwed into the boiler until the parts *P* project beyond the inner surface of said boiler. The valve *q* being opened, the steam rushes through the passage-way *b* and into the chamber *f*, pressing 100 the valve *h* to its seat, so that no steam or water can escape. By raising the free end of

the lever *n* the steam, if there be any in the boiler, will rush from the chamber *f* through the channels *g g* in the valve-stem, thereby showing that there is water in the boiler. As soon as the lever *n* is released the steam-pressure will at once press the valve *h* to its seat and cut off the flow of steam. Ordinarily the valve *q* is left open; but in case the valve *h* for any reason does not work properly the valve *q* may be closed, when the valve *h* and its connecting parts may be removed for cleaning and repairing.

Having thus described my invention, what I claim to have invented, and desire to secure by Letters Patent, is—

In a water-gage cock, a bored stem adapted to be connected with a steam-boiler and the bore serving for the passage of steam, a valve carried by the stem, detachably mount-

ed and held normally closed by the pressure of the steam thereagainst, a hand-lever fulcrumed upon the stem, an angular arm jointed to said lever, one of the branches having a bifurcation, the outer end of the valve-stem being grooved to receive said bifurcation and the other branch of the arm extending freely through an opening in the outer end of the first-mentioned stem, and a second valve carried by said first-mentioned stem between the exhaust-valve and the boiler end of the first-mentioned stem.

In testimony whereof I have hereunto set my hand in presence of two subscribing witnesses.

JENS C. JENSEN.
